(57) CLAIM

The ornamental design for a long vehicle monitor pod, as shown and described.

DESCRIPTION

FIG. 1 is a perspective view of a long vehicle monitor pod carrying a monitor in phantom outline, showing my new design;

FIG. 2 is a top plan view;

FIG. 3 is a bottom plan view;

FIG. 4 is a front elevational view;

FIG. 5 is a rear elevational view;

FIG. 6 is a side elevational view; and,

FIG. 7 is a side elevational view opposite the side of FIG. 6. The broken line showing of environment is for illustrative purposes only and forms no part of the claimed design.
